United States Patent Office

Des. 180,303
Patented May 14, 1957

180,303

DUST PAN OR SIMILAR ARTICLE

William D. Timmons, Coshocton, Ohio

Application August 23, 1954, Serial No. 31,979

Term of patent 14 years

(Cl. D44—18)

Fig. 1

Fig. 2

Fig. 3

Fig. 4

Fig. 1 is a top plan view of a dust pan or similar article, showing my new design;

Fig. 2 is a front elevational view thereof;

Fig. 3 is a cross-sectional view on the line 3—3 of Fig. 1; and

Fig. 4 is a fragmentary cross-sectional view on the line 4—4 of Figure 1.

I claim:

The ornamental design for a dust pan or similar article, substantially as shown.
